DESIGN FOR A COMBINED FLOWER POT AND STAND

Abraham S. Caplan, Brookline, Mass., assignor to Premier, Inc., Boston, Mass., a corporation of Massachusetts

Application November 2, 1943, Serial No. 111,570

Term of patent 7 years

To all whom it may concern:

Be it known that I, Abraham S. Caplan, a citizen of the United States, residing at Brookline, county of Norfolk, and State of Massachusetts, have invented a new, original, and ornamental Design for a Combined Flower Pot and Stand, of which the following is a specification, reference being had to the accompanying drawing, forming a part thereof.

I claim:

The ornamental design for a combined flower pot and stand, as shown.

ABRAHAM S. CAPLAN.
